PROCESS OF TREATING OILS

Filed May 18, 1921

UNITED STATES PATENT OFFICE.

FRANK A. HOWARD, OF ELIZABETH, NEW JERSEY, ASSIGNOR TO STANDARD OIL DEVELOPMENT COMPANY, A CORPORATION OF DELAWARE.

PROCESS OF TREATING OILS.

Application filed May 18, 1921. Serial No. 470,568.

This invention relates to a process of treating hydrocarbon oils and more particularly to a process wherein heavier constituents of said oils are converted by heat treatment into low boiling products and any low boiling products or constituents naturally contained in the said oils are simultaneously removed therefrom. It is illustrated by the accompanying drawing, in which the figure shows a diagrammatic view of apparatus suitable for carrying the process into effect.

The oils used may be of any desired character, a characteristic of the present process being that it is adapted to handle a very wide variety of stocks, including many of types not hitherto readily subjected to heat conversion treatments by known methods owing to the heavy deposits of coke which they leave in the apparatus. The present process may be carried out, for example, on heavy asphaltic oils such as Mexican crude petroleum of say 0.966 to 0.996 specific gravity and containing low proportions of low boiling constituents, such as oil having, for example, 5 to 10% of natural gasoline and kerosene.

Cold fresh stock is fed from any suitable reservoir 5 through pump 6 and meter 7 to heat exchanger 8, in which it receives an initial preheating. From heat exchanger 8 it passes through pipe 9 and coil 10 in the second heat exchanger 11 and into the chamber or drum 12, where the stock is deprived of its natural naphtha, a process known as "skimming." From this drum or still the vapors evolved from the oil pass through vapor line 13 to condenser 14, from which condensates pass through sight-box 15 to receptacle 16.

From the drum or still 12 the skimmed oil or residues pass out through pipe 17 and are forced by pump 18 through pipe 19 to a fired coil 20. In practice it has been found feasible to use about 4" pipes for this coil, and the aggregate length may be about 1600 feet, although either dimension may be very widely varied. The speed with which the residue is fed by pump 18 is adjusted to the firing rate so that the oil emerging from the coil 20 has a temperature between 750 and 900° F., say about 800° F., and the velocity in the coil is made sufficiently high that there is substantially no coke deposited in the coil. A feed rate 2,000 gallons per hour has

been successfully employed. The velocity of the oil in the coil may be modified in different ways without lowering the temperature of the outgoing oil. The obvious method is to increase the firing rate and the feed rate simultaneously so as to increase the velocity without lowering the outgoing temperature. In any given apparatus this expedient may be sufficient to prevent coke deposition. It may be found, however, that with the maximum firing possible in the apparatus it is impossible to obtain sufficient velocity to prevent coke deposit without increasing the feed rate to a point sufficient to lower the outgoing temperature of the oil below that desired. In that case the velocity may be increased by injecting steam or other gaseous fluid into the oil stream, as by the valve 21 which is provided for that purpose. The steam, spreading through the oil body in the form of bubbles, greatly increases the volume and therefore greatly increases the velocity without absorbing any proportionate amount of heat in transit. Thus the actual oil velocity through the coil 20 can be raised to any desired extent by steam or gas injection whenever it is found that the limitations of the particular apparatus chosen prevent increase in velocity without loss of outgoing temperature. Avoidance of coke in coil 20 is principally due to the fact that while the oil is raised to a temperature ordinarily considered to be an effective cracking temperature, it remains in the coil for so brief a period that only incipient cracking occurs, and the oil leaves the coil substantially unchanged, a drop in viscosity and a small decrease in specific gravity being the only effects produced therein.

From coil 20 the oil enters drum 22, which is mounted in a setting 23 in such manner as to receive the flue gases from the setting for the coil 20. In this drum the velocity of the oil is greatly reduced and its size is such that the oil remains in it for a considerable period, in practice, about 1½ hours. Copious deposits of coke may occur in this drum. For this reason only sufficient heat is supplied to prevent great loss in temperature, this being effected, as illustrated, by using the waste gases from the furnace heating the coils 20. This relatively small heating is insufficient to endanger the walls of the drum in spite of the copious coke deposits.

The oil leaving the drum 22 has a temperature of 720° F. or higher. The outlet pipe 24 leaving drum 22 is connected to the highest point on the drum to prevent trapping. From the drum 22 the treated oil, including all the mixed products of conversion, passes through outlet pipe 24 and coil 25, which is located within the drum or still 12, and through control valve 26 by means of which 10 a considerable pressure is maintained within the system. This pressure is sufficient to maintain the oil charged by the pump 18 into the pressure system in the liquid phase until modified by heat conversion. In the 15 case described, this pressure may suitably be 150 pounds per square inch or higher. The treated oil, after passing through pressure control valve 26, enters the drum or container 27 above the horizontal baffle 28. By 20 reason of the reduction in pressure upon the liquid, there is a considerable evolution of vapors in drum 27 in addition to the vaporized materials carried through the pressure system. These vapors pass out through pipe 25 29 into coil 30 in the drum or heat exchanger 8. This coil may suitably be provided at an intermediate point with a trap 31, from which liquid products condensed at that point are drawn off through pipe 32 to cooling worm 33, from which they pass through sight-box 34, to receptacle 35. Vapors continue through the coil 30 to condenser 36, from which condensate passes through sight-box 37, to receptacle 38. 35 The crude oil or initial stock, in passing through the heat exchanger 8, is initially heated by the vapors issuing from the low pressure drum 27 and passing through coil 30. It then passes through the coil 10 in 40 heat exchanger 11 in which it is further heated by the bottoms or residues from the converted oil, which enter the preheater or heat exchanger 11 through pipe 39 and leave it through pipe 41. The oil then enters the 45 drum or still 12, in which it is further heated by the products of conversion issuing from the drum 22 through coil 25 under pressure. Here the vapors of low boiling products are given off from the oil, passing out through 50 vapor line 13 to a suitable condenser system, while the residues from the oil are forced by the pump 18 through the pressure system as hereinbefore described. The oil attains a temperature of 450 to 550° F. by the time 55 it leaves the drum 12. All of the natural gasoline and some of the kerosene pass off through the vapor line of the drum 12. The residues, which in the case of an oil of the character above described, will have 60 a specific gravity of 0.993 to 1.014, will be so converted in its passage through the pressure system as to produce 20 to 25% or upwards of its own volume of distillate having a specific gravity of, for example, 0.788 and a residue of reduced viscosity.

The rate of feed and withdrawal of oil from the pressure coil 20 and drum 22 should be adjusted to produce approximately the conversion described.

I claim:

1. The method of simultaneously skimming and cracking hydrocarbon oil which comprises flowing hydrocarbon residue through a conduit heated to a temperature such that the oil attains a temperature of 75 750 to 900° F. while traveling therethrough with a velocity such as to prevent substantial deposition of carbon therein, passing the oil into an enlarged drum, holding the liquid oil in said drum at a temperature above 720° F., exerting pressure upon the oil in the conduit and drum to maintain the unchanged charging stock in liquid phase, continuously drawing off the mixed products 80 of conversion from the top of the drum, conveying the products into a chamber in which pressure is released, separately withdrawing the vapors and residues from said chamber, passing crude oil containing low boiling point constituents successively into heat-exchange contact with the vapors from the last 85 mentioned chamber, the residues from said chamber and the converted products issuing from the enlarged drum while passing from the enlarged drum to the chamber in which 90 pressure is released, separately withdrawing the vapors given off from the crude oil and introducing the residue therefrom into the first mentioned heated conduit.

2. The method of treating oils to remove 100 natural low boiling constituents therefrom and effect conversion of high boiling constituents of the residue to low boiling products which comprises heating residues to temperatures sufficient to effect conversion 105 of high boiling constituents into low boiling products under pressure sufficient to maintain unchanged residue in the liquid phase, conveying the mixed products of conversion into a chamber at lower pressure, removing the products therefrom, passing 110 fresh oil containing low boiling constituents into heat exchange relation with the conversion products at lower pressure removed from said chamber, and subsequently into 115 heat exchange relation with the conversion products at higher pressure before they enter said chamber without at any time permitting admixture of said fresh oil and said conversion products, withdrawing the 120 vapors evolved from said fresh oil and subjecting the residue to the hereinbefore described heat treatment.

3. The method of treating oils to remove 125 natural low boiling constituents therefrom and effect conversion of high boiling constituents of the residue to low boiling products which comprises heating residues to temperatures sufficient to effect conversion of high boiling constituents into low boil-

ing products under pressure sufficient to maintain unchanged residue in the liquid phase, conveying the mixed products of conversion into a chamber at lower pressure, 5 separating the vapor and liquid products of conversion, passing fresh oil containing low boiling constituents into heat exchange relation with the separated vapor and liquid conversion products in succession, then pass- ing the oil into heat exchange relation with 10 the mixed conversion products before they enter the low pressure chamber without at any time permitting admixture of said fresh oil and said conversion products, withdrawing the vapor evolved from the heated 15 fresh oil and subjecting the residue to the heat treatment hereinbefore described.

FRANK A. HOWARD.
